UNITED STATES PATENT OFFICE.

JOHN WILLIAM NOLAN, OF PAWTUCKET, RHODE ISLAND, ASSIGNOR TO WILLIAM H. THORNLEY, OF PROVIDENCE, RHODE ISLAND; ELLEN S. THORNLEY EXECUTRIX OF SAID WILLIAM H. THORNLEY, DECEASED.

AUTOMATIC FUSE CUT-OUT.

Application filed November 12, 1917, Serial No. 201,547. Renewed October 26, 1921. Serial No. 510,534.

This invention relates generally to electrical appliances, and more particularly to fuse cut-outs used in connection with three-phase electrical circuits, or to four wire two-phase circuits, etc.

The primary object of the invention is to provide a mechanically operated means whereby when a fuse in any one of the circuits is blown, the switch in another circuit 10 will be automatically opened so that all of the power circuits are open. In three-phase circuits, now commonly used, one of the fuses may be blown, but this does not entirely break the circuit since it will continue to operate on a one-phase circuit tending to overheat the motor, with a consequence of overheating, overloading and unbalancing of the entire circuit, and difficulties well known to those skilled in the art will be experienced.

20 By means of this invention however, immediately upon any one of the fuses being blown, the switch of an adjoining phase of the same circuit will be opened, thus altogether stopping flow of current to the motor.

The above mentioned object of the invention is attained by the combination and arrangement of parts and the details of construction as will be hereinafter fully described and claimed.

In the accompanying drawings forming part of the application and wherein;

Fig. 1 is a diagrammatic representation of a three-phase electric circuit employing devices constructed in accordance with this invention therein;

Fig. 2 is a side elevation of one of the devices or combined switches and fuses;

Fig. 3 is a sectional view taken on the plane indicated by the line 3—3 of Fig. 2;

Fig. 4 is a central vertical sectional view of the switch and fuse;

Fig. 5 is a sectional view taken on the plane indicated by the line 5—5 of Fig. 4;

Fig. 6 is a front view of the fuse member and the pins to which its ends are connected; and

Fig. 7 is a sectional view taken on the plane indicated by the line 7—7 of Fig. 4.

In the drawings above briefly described similar reference characters are placed upon corresponding parts throughout the several views and reference is herein made to the various elements by their respective indices.

To this end numeral 1 designates a non-conducting base plate upon which is mounted a switch blade 2, the latter being pivoted at one of its ends by means of a pin 3 which extends through a pair of posts 4 secured to one side of the base plate. Secured also to the base plate 1 is a contact clip 5 which is engaged by the other end of the switch blade 2 when the switch is in closed position. Conducting wires are adapted to be connected to the post 4 and the clip 5 so that when the blade 2 is in engagement with the latter the connection between these wires will be completed.

Secured rigidly to the base plate 1 and extending outwardly from the same is a supporting arm 6. This arm 6 is of non-conducting material, preferably fiber, and carries at its outer end a metallic head 7, the latter having a vertical aperture 8 therein through which a conductor rod 9 is extended. The rod 9 is maintained in fixed relation to the head 7 by means of set screws 10. Threaded upon the lower end of the rod 9 is a binding nut 11 between the inner end of which and the lower side of the head 7 is clamped one of the circuit wires. The other end of the rod 9 is flattened as at 12 and extends into the lower end of an insulating tube or casing 13 and passes through the lower insulating disks 13' and 13^a which are arranged within the lower end portion of the tube 13. The upper end of the rod 9 is connected to an element or strip 14, and the upper end of this strip 14 is connected to the lower end of a second conductor rod 15 which latter is similar and complementary to the element 9 and extends through upper insulating disks 13' and 13^a and through an aperture 16 which extends vertically through a metallic head 17 carried on the outer end of a movable arm or lever 18. The elements 9 and 15 also pass through packing and insulating material 13'' such as asbestos or the like, this packing being sufficiently loose around the element 15 to permit the latter to be slid therethrough and through the disks 13' and 13^a by the upward movement of the head 17 of the lever 18. The inner end of this lever 18 is pivoted between a pair of posts or bearings 19 secured to the base plate 1. The rod 15 is held in fixed relation to the head 17 by means of set screws 20, and threaded upon the upper end of the

pin is a binding nut 21 between the inner end of which and the upper side of the head 17 is clamped another of the circuit wires.

It is to be understood that the elements 5 9 and 15 are conductors through which the current passes to and from the fusible element 14.

The lever 18 carries a depending lug or 10 nose 22 which engages the switch blade 2 and holds the same in closed position against the tension of a spring 23 which bears against the same and tends to throw the switch blade into open position. The outward movement of the switch blade is limited by a yoke 24 15 carried by the base plate 1.

Normally the fuse strip serves as a tie or 20 tension member to hold the switch restraining lever 18 in the position for holding the switch closed. But when the fuse strip becomes overheated by excessive current and is 25 melted, or so much softened that it no longer has strength to hold said restraining lever, then the stress constantly exerted from the spring 23 through switch blade 2, lug 22 and 30 restraining lever 18 causes the fuse to part. Preferably the fuse is provided with a portion of reduced cross sectional area in its 35 middle in order that the parting may occur at a definitely known point. As the tube 13 and insulating heads 13^a are not connected to the metallic heads 7 and 17, except as 40 they are tied thereto by the fuse strip and associated conductors 9 and 15, such casing does not prevent such displacement of the restraining lever 18 as is necessary for the 45 result just described to take place. The casting and the asbestos packings in the ends thereof prevent damage being caused by sparks or hot metal when the fuse is blown, while the quick separation of the parts of 50 the fuse caused by the spring driven movement of the restraining lever suppresses the tendency of an arc to form between the terminals of the ruptured fuse.

Heretofore great difficulty has been experienced in three-phase three-wire electric 55 circuits because where one of the fuses is blown the circuit is not entirely broken since it will continue to operate on a one-phase circuit through the other two wires. To 60 overcome this difficulty, three of the above described devices or combined switches and fuses are employed, and the manner in which this is done is illustrated diagrammatically in 65 Fig. 1. In this view the three circuit wires are designated 25, 26 and 27, and the switches are designated 28, 29 and 30, each switch being a duplicate of the unit just described in detail. Each of the circuit wires is connected with one end of the fuse of one 70 switch, and the other end of said fuse is connected by a wire, 31, 32 or 33 respectively, with the contact clip 5 of another switch. Thereby the circuit wire 25 is connected with 75 the conductor 36 leading from switch 30, the

circuit wire 26 is connected with the conductor 34 leading from switch 28 and the circuit wire 27 is connected with the conductor leading from the switch 29. It will thus be seen that the circuit of each of the wires 25, 26 and 27 passes through the fuse strip of one of the switches and then through the switch blade of another so that in case one fuse is blown, its switch blade will be opened to open the circuit through another of the wires. This obviously breaks the circuit through two of the wires and prevents it from working on a one-phase circuit to overheat and otherwise damage the devices operated by the same.

From the foregoing, taken in connection with the accompanying drawings, the construction, use and operation of the device will be readily understood without a more extended explanation.

As various changes in form, proportion and in the minor details of construction may be resorted to without departing from the spirit of this invention, it is to be understood that I do not wish to be limited to the construction herein shown and described other than as claimed.

I claim:

1. In combination a polyphase circuit having a number of conducting lines, circuit controllers each consisting of a switch and a fuse, the fuse of each controller being connected with one of the conducting lines and with the switch of another controller, and the switch of each controller being in the circuit of a different line from that in which its own fuse is connected and each controller including means tending to open its switch and restraining means connected with its fuse and effective to maintain the switch in closed position while said fuse retains its integrity.

2. The combination of a plurality of circuit controllers each including a switch having separate terminals, a fuse, a spring tending to open said switch, and restraining means normally held by the associated fuse in position to prevent opening of the switch, said controllers being coupled with the lines of a polyphase circuit in such fashion that the fuse of each controller is arranged in series in the same line with the switch of a different controller.

3. A safety circuit controller comprising a switch adapted to be connected with one of the conductors of a polyphase circuit, means tending to open said switch, a restraining device adapted to hold said switch in closed position when itself restrained from displacement, but being arranged and located so that the force of said switch-opening means acting through the switch tends to displace it out of the switch-holding position, and a fusible conductor coupled with said restraining device and ar-

ranged to prevent such displacement thereof, said fusible conductor being connected with a different conductor of the circuit than that with which said switch is connected.

4. A circuit controller for polyphase circuits comprising a switch in connection with one phase of such a circuit and being under tendency constantly to open, a restraining device for such switch having a portion overlapping a part of the switch and being so mounted that force exerted by the switch tends to displace it to a position wherein it no longer opposes opening movement of the switch, and a fuse in connection with a different phase of the circuit coupled to such restraining device and normally preventing such displacement thereof, but adapted to release the restraining device when its integrity is destroyed by fusing.

5. A polyphase circuit controller comprising a switch electrically connected in one phase of the circuit, said switch including a pivotally mounted blade under tendency constantly to move into open position, a restraining device having a lug overlapping a part of said switch blade and being mounted to move in a path which permits displacement of said lug out of engagement with the switch blade, said lug being arranged so that the force exerted by the switch blade tends so to displace it, and a fuse electrically connected in a different phase of the circuit and mechanically connected with said restraining device so as to prevent displacement thereof while its own integrity continues:

6. A safety controller comprising a switch connected with one conductor of a polyphase circuit and including a pivoted switch blade under constant tendency to be moved into open position, a pivoted restraining device having a lug overlying a part of said blade and so arranged that the force exerted by the opening tendency of the blade tends to move said lug about the pivot of the restraining member, such movement of the lug being in a path which carries it out of the path in which the switch blade moves when opening, a fixed abutment, and a fuse connected to said abutment and to said restraining device in position to hold the latter in its restraining relation to the switch, said fuse being electrically connected in a second phase of the circuit.

7. A safety controller for polyphase circuits comprising a switch electrically connected with one of the phases of such circuit, a lever fulcrumed in a position to engage with and normally hold the switch closed and to be swung about its fulcrum by the opening movement of the switch, a fusible conductor in electrical connection with a second phase of the circuit being mechanically coupled with said lever, means nor-

mally coacting with said fusible conductor to hold said lever in its switch holding position, and means normally tending to open said switch against the holding tendency of said lever and fusible conductor.

8. A safety polyphase circuit controller comprising a switch adapted to be connected with one of the conductors of a polyphase circuit, a fusible conducting element adapted to be connected with a second conductor of such circuit, a movable holder secured to the fusible conducting element and held thereby against movement, means for opening the switch, and means normally coacting with said fusible conducting element and holder to hold said switch closed, but allowing the latter to be opened by the first said means when the fusible conducting element is fused.

9. The combination with a polyphase circuit of means for breaking the circuit of one phase by the breaking of a circuit of another phase comprising an independently openable circuit breaker element in the circuit respectively of each phase adapted to be controlled by a predetermined current in its circuit, a second circuit breaking element respectively in the circuit of each phase resiliently pressed in a direction to open the circuit of its respective phase, and each of said second circuit breaking elements being openable independently of each other, and means whereby the opening pressure on each of said second circuit breaking elements is respectively transmitted to one of said first circuit breaking elements connected in a different phase.

10. The combination with a polyphase circuit of a circuit breaking element in the circuit of each of said phases respectively and each of said elements being openable independently of each other, a second circuit breaking element in the circuit of each of said phases respectively, and openable independently of each other, the first named elements of each phase being in series respectively with the second named elements of each phase, and means for causing the opening of one of said second named elements upon the opening of one of said first named elements in a different phase.

11. The combination with a polyphase circuit of a circuit breaking element in the circuit of each of said phases respectively and openable independently of each other, a second circuit breaking element in the circuit of each of said phases respectively and openable independently of each other, each of said second circuit breaker elements being biased to move to open position, and means whereby each of said second circuit breaking elements is held in closed position respectively by one of said first named circuit breaking elements connected in a different phase of the circuit.

12. The combination with a polyphase circuit of a circuit breaking element in the circuit of each of said phases respectively and openable independently of each other upon the passage of an overload current, a second circuit breaking element in the circuit of each of said phases respectively and openable independently of each other, each of said second circuit breaker elements be-

ing biased to move to open position, and means whereby each of said second circuit breaking elements is held in closed position respectively by one of said first named circuit breaking elements connected in a different phase of the circuit. 10 15

In testimony whereof I have hereunto set my hand.

JOHN WILLIAM NOLAN.
